(57) **CLAIM**

We claim the ornamental design for a hand-held dental tool, as shown.

DESCRIPTION

FIG. 1 is a perspective view of a hand held dental tool showing our new design;

FIG. 2 is a front perspective view thereof shown on an enlarged scale;

FIG. 3 is a right side elevation thereof shown on a reduced scale;

FIG. 4 is a rear elevation thereof;

FIG. 5 is a left side elevation thereof;

FIG. 6 is a bottom plan view thereof; and,

FIG. 7 is a rear perspective view thereof shown on an enlarged scale.
